ATTORNEY.

UNITED STATES PATENT OFFICE

2,347,401

PAIL COVER

Clarence P. Davey, Chicago, Ill., assignor to Wilson & Bennett Manufacturing Co., Chicago, Ill., a corporation of Illinois

Application December 9, 1940, Serial No. 369,282

5 Claims. (Cl. 221—11)

This invention pertains to heads or covers for pails, cans, or other containers and is particularly directed to the pouring means and handle mountings.

The objects of the invention are to provide an improved pail or container having a novel pouring spout; to provide a pail having a pouring spout which will permit the discharge of substantially all of the contents of the pail; to provide a rotatable pouring spout with a closure plug adapted to lock the spout in adjusted position; to provide a plug formed of sheet metal with an integrally formed handle portion; to provide a pail cover having a depression or recess to permit easy grasping of the handle; and to provide such other advantages and improvements as will appear hereinafter.

In the accompanying drawing,

Fig. 1 is a top plan view of a pail or container embodying this invention;

Fig. 2 is a partial plan view showing the spout in pouring position;

Fig. 3 is a cross sectional view on an enlarged scale taken substantially on the line 3—3 of Fig. 1;

Fig. 4 is a sectional detail taken on the line 4—4 of Fig. 2;

Fig. 5 is a perspective view of the plug or closure;

Fig. 6 is a perspective view of the spout; and

Fig. 7 is a perspective view of a portion of the cover showing the nozzle or outlet in its position before being pressed or folded over the coacting portion of the spout.

As shown in the drawing, 10 is a container such as a steel pail or can, having a top or cover 11 which may be seamed or permanently fastened thereto, or may be of any of the well known detachable types of covers. The main portion 12 of the cover is preferably raised in a common manner to provide for stacking and to provide outage space. The cover has a depression 13 adjacent to one side with an outlet orifice 14 therein. The outlet orifice is defined by an upstanding flange 15 which is formed integrally with the cover, and is adapted to be pressed or folded outwardly for engagement with the pouring spout.

The pouring spout 16 has a flat bottom with an opening 17 for receiving the flange or wall 15. The spout also has a peripheral body or wall portion 18 with a pouring lip or projection 19. The annular body portion of the spout is provided with threads or lugs 20 for engagement with corresponding screw threads or lugs

on the plug. After the pouring spout has been placed in position, the flange or wall 15 is pressed outwardly and downwardly over the adjacent portion of the bottom of the spout as shown particularly in Figs. 3 and 4. These parts are pressed closely together, but sufficient play or clearance is provided so that the spout may be rotated in the bearing thus formed for it. The outlet may be provided with a temporary sealing cap 21 which is removed when the pail is to be emptied. The outlet is further closed by means of a cap or plug 22 which is preferably formed of sheet metal such as sheet steel and is provided with peripheral threads or lugs 23 for engagement with the corresponding threads or lugs 20 in the pouring spout. The plug has an upwardly raised handle or thumb piece 24 for turning same. This handle or bar is preferably formed integrally with the cap or plug as shown.

20 The cap or plug 22 is also preferably provided with peripheral grooves and beads 25 to stiffen the same, and to insure close contact with a gasket or washer 26 which is interposed between the cap or plug and the adjacent flange 15. The

15 pouring spout may also be provided with a cover 27 of any usual or preferred form.

When the pail is to be filled or shipped, the spout will be swung back in the recess 13 as shown in Fig. 1, and when the plug 22 is tightened 30 to close the outlet, it will press downwardly on the gasket and tend to raise the body portion of the spout so that the bottom will be drawn tightly against the flange 15, whereby the spout will be locked or tightly fastened in position. Furthermore, as the closure between the plug and the cover is directly against a portion of the cover, there will be no likelihood of leakage around the outlet. When the contents of the can are to be poured out, the plug is removed which releases

35 the spout and permits it to be readily turned to pouring position as shown in Fig. 2, in which position the spout preferably extends sufficiently over the rim of the container so that none of the contents being poured are apt to run down

40 on the container. A projection or stop 28 is pressed upwardly from the cover, and serves to limit the swinging movement of the pouring spout which engages therewith when it is in proper position for pouring as shown in Fig. 2. The 45 parts are so proportioned that the pouring spout and coacting parts preferably do not extend above the top wall 12 of the cover so that they do not interfere with the stacking.

The cover is also provided with a central depression 29 for a swinging handle 30. The handle

is pivotally secured in position by a plate or hinge member 31 and is adapted to swing upwardly for convenience in carrying or handling the pail. The cover has a further recess or depression 32 below the grip portion of the handle when it is in lowered position as shown in Fig. 3, which permits the fingers to project under such handle portion, and facilitates the raising of the handle out of its depression.

From this description and the drawing, it will be seen that none of the parts of the pouring spout or its mounting extend inwardly or downwardly below the cover whereby the contents of the pail may be entirely discharged. Furthermore, the simple construction facilitates the ready and economical manufacture of the container. The container shown and described is a practical embodiment of my invention, but it may be changed in the proportion of the parts or the arrangement of the same in order to adapt it to different containers. Therefore, I do not wish to be limited to such embodiment except as specified in the following claims in which I claim:

1. The combination with a pail cover, of a pouring spout having a cup shaped body portion having a round hole therein and an outwardly extending pouring lip, a flange defining an opening in the cover and projecting through said hole and outwardly over the adjacent portion of the pouring spout to provide a rotatable bearing for the spout, and a plug having threaded engagement with the spout and seating against the outwardly extending portion of the flange for closing said opening and fastening the spout against rotative movement the arrangement being such that substantially no portion of the bearing assembly extends below the cover and full drainage is provided.

2. A top or cover for pails or the like, having a pouring opening adjacent to one side, the wall of the cover extending upwardly and outwardly around said opening, a pouring spout having a hole in the bottom thereof engaging with the upwardly extending portion of the wall around the hole and extending inwardly between the cover and the outwardly extending portion of said wall to provide a rotatable bearing for the spout, a gasket engaging with the outwardly extending portion of the wall, and a plug having threaded engagement with the spout and adapted to press against the gasket to draw the coating parts together to lock the spout in adjusted position and to make a tight closure the arrangement

providing a free and unobstructed outlet for the pail.

3. A pail cover, the main portion of which is raised above the top edge or head of the pail, a depression in said raised portion adjacent to one side of the pail, a flange formed integrally with the cover and extending upwardly and outwardly around a hole in the cover, a non-resilient pouring spout rotatably mounted on said flange portion and adapted to swing in a horizontal plane inwardly into the depression and outwardly to pouring position, a stop on the cover to stop the spout in pouring position, and a plug having threaded engagement with the spout and adapted to coact with the flange for closing the hole and also for locking the spout in adjusted positions.

4. A pouring assembly for a container, including a pivoted spout having a body portion with an extended pouring lip, said body portion having a bottom with a round hole therein, a container head having a circular flange extending upwardly through the hole in said body portion and fitting closely therein, said flange having a peripheral edge extending outwardly and engaging closely with the adjacent upper surface of said bottom portion of said pivoted spout to provide a joint between the spout and the head whereby the spout may be rotated in a horizontal plane with respect to the flange, said flange extending entirely upwardly from the head and providing a full clear opening through the head to give complete drainage, a plug having threaded engagement with the body portion of the spout and adapted to engage with the outwardly extending edge portion of the flange when in closing position, and a stop on the cover for stopping the spout in pouring position.

5. A container having a head provided with a circular outlet orifice which is defined by an outwardly projecting flange formed integrally with the head and which gives a free outlet opening providing for full drainage of the container, a pouring spout having a flat bottom with an opening through which said flange extends, the peripheral edge portion of the flange fitting closely against the adjacent surface of the bottom and providing a joint between the spout and the head, whereby the spout may be rotated in a horizontal plane, a gasket engaging with said outwardly extending flange portion, and a plug having threaded engagement with pouring spout and closing against said gasket.

CLARENCE P. DAVEY.
